ABSTRACT

A rocket device comprising an elongated generally tubular shaped housing; a propulsion charge in one end of the housing; means for directing the products of combustion of the propulsion charge rearwardly of the housing in a manner so as to impart rotary motion to the device as it is propelled forwardly by the charge; signal means in the form of a quantity of radar signalling chaff in the housing; an expulsion charge for expelling the signalling means from the housing; means including a combustable material within the housing for igniting the expulsion charge at a predetermined time after the propulsion charge has been ignited, and an enclosure for operatively supporting the combustable material within the housing and for preventing the ignited portion of the combustable material from being forced out of the enclosure under the influence of centrifugal force resulting from rotation of the device.

**ROTATABLE ROCKET HAVING MEANS FOR
PREVENTING FLAMEOUT DUE TO
CENTRIFUGAL FORCE CREATED DURING
ROTATION THEREOF**

This application is a continuation-in-part of Application Ser. No. 694,208, filed Dec. 28, 1967, and now abandoned.

BACKGROUND OF THE INVENTION

Extensive research into rocket type projectiles has indicated that gyroscopic stabilization thereof maximizes the control and efficiency of flight trajectory. Accordingly, such gyroscopic stabilization techniques have been incorporated in a variety of different types of rocket-like devices, including rocket devices of the type used for personnel rescue and similar type signaling purposes. By way of example, common types of rescue rockets incorporate pyrotechnic or combustable illuminatable substances or, alternatively, various types of radar sensing chaff, the presence of which may be noted by various types of electronic searching and scanning devices such as radar or the like.

It is the common practice in such rescue rockets to provide a propulsion charge adapted to propel the rocket to a predetermined altitude and an expulsion charge which functions to expel a particular signaling apparatus, such as the aforementioned pyrotechnic or chaff type devices, away from the rocket a predetermined time after the propulsion charge has been ignited. In order to provide for a delayed ignition of the expulsion charge, a delay train or timing fuse is usually provided in such signaling or rescue rockets. Commonly, the delay train is in the form of a charge of a combustable material which turns to a semi-liquid state upon ignition thereof and is adapted to burn at a predetermined rate preparatory to effecting ignition of the associated expulsion charge.

Although the aforementioned delay trains or timing fuses have functioned satisfactorily in conventional rockets, such devices for delaying the ignition of the expulsion charges in rescue type rockets have been objectionable when such rocket devices have incorporated means for providing for gyroscopic stabilization thereof. The reason for this is that once such gyroscopically stabilized rockets have been launched, they rotate at a predetermined speed as they are propelled along their flight path in order to effectuate stable flight; however, it has been found that such rotative movement of the rocket creates a centrifugal force upon the combustable material of the delay train of sufficient magnitude to force or throw the ignited material out of its respective enclosure within the rocket, with the result that the delay train suffers what is commonly known as a "flame-out" or a cessation of ignition. Of course, when the delay train experiences such a malady, the associated expulsion charge is not ignited at the predetermined time and the signaling device incorporated in the rocket is not expelled and is thus rendered inoperative.

In accordance with the principles of the present invention, the aforementioned objectionable characteristics heretofore experienced in gyroscopically stabilized rescue rockets is virtually entirely overcome through the provision of a novel rocket device incorporating a delay train or timing fuse having means adapted to prevent the combustable material disposed

within the delay train enclosure or housing from being thrown outwardly therefrom under the influence of centrifugal force during the forward propulsion of the rocket. Such means is provided by a generally inwardly extending wall portion provided at the lower or discharge end of the enclosure for the delay train, which wall functions to retain the ignited combustable material within the enclosure during the time the rocket is being propelled. Accordingly, the ignited material will not be forced out of the delay train enclosure, with the result that possible flame-out conditions are effectively and positively prevented.

SUMMARY OF THE INVENTION

This invention relates generally to rocket-like devices and, more particularly, to a rocket propelled device for projecting a radar signaling material to an altitude such that said material may be detected by radar or the like.

It is accordingly a generally object of the present invention to provide a new and improved radar signaling rocket.

It is a more particular object of the present invention to provide a new and improved rocket device for projecting radar signaling chaff to an altitude where such material may be detected as by radar.

It is still a more particular object of the present invention to provide a new and improved radar signaling rocket of the type which rotates as it is projected forwardly, and which includes means for preventing the combustable material comprising the delay train thereof from being forced from its associated enclosure means within the rocket housing under the influence of centrifugal force resulting from rotation of the rocket.

It is another object of the present invention to provide a new and improved device of the above character which includes a generally restricted or reduced diameter discharge opening in the enclosure means for the combustable material of the delay train, the discharge opening being defined by a generally inwardly extending wall portion that prevents any of the ignited combustable material for being forced out of the lower end of the delay train enclosure.

It is yet another object of the present invention to provide a new and improved radar signaling rocket of the above character which is of a simple design, is easy to assemble and economical to commercially manufacture.

Other objects and advantages of the present invention will become apparent from the following detailed description taken in conjunction with the accompanying drawing.

BRIEF DESCRIPTION OF THE DRAWING

FIG. 1 is a longitudinal cross sectional view of a radar signaling rocket in accordance with a preferred construction of the present invention;

FIG. 2 is an end elevational view of the rocket illustrated in FIG. 1, as seen in the direction of the arrow 1 thereof, and

FIG. 3 is an enlarged fragmentary view of the portion of the rocket illustrated in FIG. 1, as taken within the oval 3 thereof.

DESCRIPTION OF A PREFERRED EMBODIMENT

For purposes of description, the terms "forwardly" and "rearwardly" will have reference to the rescue rocket of the present invention as shown in FIGS. 1 and 3 of the drawing, with the forward end of the rocket being located at the right side of these figures and the rearward end being located at the left side of said figures. Also, the terms "inwardly", "outwardly" and derivatives thereof will have reference to the geometric center of the rocket device of the present invention and the various component parts thereof.

It will be noted that the principle of the present invention will find particularly useful application when incorporated in rocket-like devices of the type used for personnel rescue purposes. Accordingly and by way of example, the present invention is illustrated herein in operative association with a radar type rescue rocket. It will be readily apparent, of course, that the scope of the present invention is not intended to be limited to the illustrative embodiment shown and described herein since wide and varied alternative applications will be obvious to any person skilled in the rocketry art.

Referring now in detail to the drawing, a signal or rescue rocket, generally designated by the numeral 10, is shown as comprising an elongated cylindrical casing or housing 12 that is substantially closed at the rearward end thereof by a generally transversely extending nozzle plate 14. The plate 14 is formed with an annular recess 16 around the outer periphery thereof and is adapted to be fixedly secured within the rearward end of the housing 12 by having a portion of the housing 12 swaged or deformed radially inwardly into engagement with the periphery of the recess portion 16, as seen at 18 in FIG. 1. The nozzle plate 14 is formed with a plurality of discharge orifices 20 equally circumferentially and radially spaced therearound, as best seen in FIG. 2. The orifices 20 are communicable at their forward ends with the interior of the housing 12 and are communicable at their rearward ends with generally rearwardly tapered enlarged diameter wall portions, generally designated 22. As illustrated in FIG. 2, the tapered wall portions 22 are canted or inclined in the same circumferential direction, i.e. counterclockwise, for reasons later to be described in effecting rotational stabilizing movement of the rocket 10 as it is propelled forwardly.

The nozzle plate 14 is provided with a centrally located primer or similar type ignition device which is fixedly mounted within a suitable primer seat or opening 26 formed in the plate 14. Extending across the interior or forwardmost side of the nozzle plate 14 is relatively thin, preferably rupturable, diaphragm member 28 that is fabricated of a relatively thin sheet of aluminum which may, for example, be secured to the forward side of the nozzle plate 14 by a suitable pressure or heat sensitive adhesive. The diaphragm 28 functions both as a hermetic seal for the lower end of the rocket 10, and to facilitate pressure buildup internally of the housing 12 upon firing of the primer 24.

Disposed within the rearward end of the housing 12 immediately forwardly of the diaphragm 28 is a quantity of propellant which may be of any suitable type known in the art. The propellant is in the form of a generally cylindrical charge 30 having generally frustoconical recessed portions 31 formed at the forward and

rearward ends thereof, the recessed portions 31 being connected by means of an axially disposed central passage 32 which extends the entire length of the charge 30. Preferably, the outer diameter of the cylindrical charge 30 is substantially the same size as the inner diameter of the housing 12 whereby to preclude any relative movement therebetween upon assembly of the rocket 10.

Referring now to the forward end of the housing 12 and to the signaling or rescue device incorporated in the rocket 10, there is provided a generally elongated cylindrical or tubular casing 34, the outer diameter of which is adapted to be slightly smaller in size than the inner diameter of the housing 12, whereby the casing 34 may be nestingly received within the forward end of the housing 12, as illustrated in FIG. 1. The forward end of the casing 34 is closed by a transversely extending partition member or end plug 36 which may be press fitted within the forward end of the housing 12, as shown in FIG. 1. The rearward end of the casing 34 is closed by another transversely extending partition member 38 which is also press fitted within the interior of the housing 12 and is preferably fabricated of a felt-like material. The partition member 38 is designed to protect the contents of the casing 34 from the products of combustion of the expulsion charge used to expel the casing 34 from within the housing 12, as will later be described. In the embodiment of the present invention illustrated herein, the interior of the casing 34 is provided with a series of adjacent chaff charges, generally designated 40, which are composed of any suitable chaff material of the type capable of being sensed on a suitable radar scanning apparatus or the like. By way of example, the chaff charges 40 may be composed of metallic particles such as wire mesh metallic shavings or the like. It will be apparent, of course, that the casing 34 may be provided with some type of signaling apparatus other than the chaff 40 as, for example, an illuminating signal device or the like.

Disposed directly rearwardly of the felt partition member 38 is a transversely extending piston that is preferably fabricated of aluminum and is adapted to be slidably disposed within the interior of the housing 12 in the manner as illustrated in FIG. 1. As will hereinafter be described, the piston 42 is adapted to move longitudinally of the housing 12 toward the forward end of the rocket 10 upon ignition of the expulsion charge in the rocket 10, thus effecting removal of the casing 34 and the chaff 40 from within the housing 12.

As best seen in FIG. 1, an annular spacer member, generally designated 44, is disposed within the housing 12 directly rearwardly of the piston member 42. The spacer member 44 comprises an annular or cylindrical section 46 that is adapted to be fixedly secured within the interior of the housing 12, as illustrated. The member 44 also comprises a transversely extending partition section 48 that projects radially inwardly from the interior of the section 46 and defines a central annular bore 49. The sections 46 and 48 of the member 44, together with the rearward side of the piston 42 define an annular cavity 50 which is filled with an expulsion charge, generally designated by the numeral 52. The charge 52 may be composed of any suitable explosive material such as black powder or a similar

material having sufficient explosive power to expel the casing 34 and chaff charges 40 contained therein from within the interior of the housing 12.

In order to effect ignition of the expulsion charge 52 at a predetermined time after the ignition of the propellant 30, the rocket 10 is provided with a delay train or timing fuse arrangement interjacent forward end of the propellant 30 and the rearward end of the expulsion charge 52. In particular, the delay train comprises an enclosure member, generally designated by the numeral 54, which comprises a transversely extending bulkhead section 56 having an annular, radially inwardly extending recess portion 58 formed therein. The member 54 is preferably fabricated of aluminum or a similar light weight material and is adapted to be fixedly secured within the housing 12 by having a central portion of the housing 12 swaged on similarly deformed radially inwardly into the recess portion 58, as seen at 60 in FIGS. 1 and 3. The member 54 comprises an integral centrally located cylindrical or tubular enclosure section 62 that projects forwardly from the forward side of the bulkhead section 56, as shown in FIG. 1, the enclosure section 62 extending forwardly through the central opening 49 and terminating at its forward end directly adjacent the expulsion charge 52 within the cavity 50. The enclosure section 62 and the forwardmost portion of the bulkhead section 56 define a generally cylindrical cavity 64 adapted to contain a combustable delay element or timing fuse 66 which may be of any suitable material adapted to burn at a preselected rate, whereby to function in igniting the expulsion charge 52 at a preselected time after ignition of the propellant 30, as will later be described.

In accordance with the principles of the present invention, the member 54 is provided with means adapted to prevent the combustable material 66 comprising the timing fuse and which transforms to a semi-liquid state as it burns toward the expulsion charge 52, from being thrown or forced out of the rearward end of the cavity 64 under the influence of centrifugal force due to rotation of the rocket 10 during its forward propulsion. Such means is provided by a generally radially inwardly extending wall portion or shoulder 68 integrally formed on the member 54 and extending inwardly from the rearward end of the cavity 64. As best illustrated in FIG. 3, the wall portion 68 defines a centrally located restricted discharge orifice 70 and is defined by a rearwardly and inwardly inclined surface or face 72 and a generally radially extending face 74 which is preferably coplanar with the rearward side of the bulkhead section 56, as shown. In a preferred construction of the present invention, the wall portion 68 encloses approximately one-half of the rearward end of the cavity 64, with the result that the diameter of the restricted orifice 70 is approximately one-half the diameter of the cavity 64. It may be noted that the relative size of the wall portion 68 with respect to the diameter of the cavity 64 may be varied in accordance with the type of material 66 comprising the delay train, as well as with the configuration of the enclosure section 62 and size of the rocket 10.

From the above description, it will be seen that upon ignition of the combustable material 66 of the delay train, the wall portion 68 will prevent the rearwardmost part of this material from being forced outwardly

through the discharge orifice 70 as the rocket 10 rotates or spins while it is projected forwardly. Accordingly, the combustable material 66, upon being initially ignited, will burn smoothly and continuously for a predetermined amount of time prior to effecting ignition of the expulsion charge 52, with the possibility of a flame-out of the material 66 being positively prevented.

In operation of the rescue rocket 10 of the present invention, the rocket 10 is adapted to be fired as, for example, from a mortar or similar type apparatus having fixed firing pin. When it is desired to fire the rocket 10, the same is dropped into the mortar with the rearward end thereof facing downward, with the result that when the rocket 10 strikes the firing pin located at the lower end of the interior of the mortar, the primer 24 will be exploded. Upon explosion of the primer 24, the diaphragm 28 is ruptured and the propulsion charge 30 is ignited, and at the same time the combustable material 66 in the delay train is ignited. The products of combustion of the propellant 30 vent through the discharge orifices 20 in the nozzle plate 14, driving the rocket 10 from the mortar and to a predetermined altitude. The angular disposition of the walls 22 adjacent each of the discharge orifices 20 causes the rocket 10 to spin or rotate about its longitudinal axis, whereby to achieve gyroscopic stabilization of the rocket 10. Upon ignition of the material 66 of the delay train, said material will begin to burn from the rearward end thereof toward the forward end, with such material being transformed into a liquid or semi-liquid state due to the heat of combustion thereof. As above described, the radially extending wall portion 68 prevents the liquid portion of the combustable material 66 from being forced out of the rearward end of the cavity 64 as the rocket is rotating, thus assuring continuous ignition of the material 66. When the rocket has been propelled to a predetermined altitude, the combustable material 66 will be completely burned out and will ignite the expulsion charge 52 disposed within the cavity 50. Ignition of the charge 52 results in explosion thereof, which in turn results in the piston member 42 forcing the casing 34 longitudinally outwardly (forwardly) from the forward end of the housing 12. As the casing 34 is forced out of the housing 12, the chaff charges 40 will be expelled into the atmosphere, which charges 40 will thereafter fall to the earth with their presence being indicated and their location being identified on a radar screen or similar type scanning and identification equipment.

We claim:

1. In a rocket device,
an elongated generally tubular shaped housing,
a propulsion charge in one end of said housing,
means for directing the products of combustion of
said charge rearwardly of said housing in a manner
so as to impart rotary motion to said device as it is
propelled forwardly by said charge,
signal means in said housing,
an expulsion charge for expelling said signal means
from said housing,
a time delay fuse comprising a combustable material
for igniting said expulsion charge at a predeter-
mined time after said propulsion charge has been
ignited, said fuse normally being in a solid state
and being transformable from said solid state to a
semi-liquid state upon combustion thereof, and

enclosure means for operatively supporting said time delay fuse within said housing, said enclosure means comprising a generally cylindrically shaped cavity located substantially coaxially of the device and terminating at one end thereof in a radially inwardly extending portion for preventing the semi-liquid ignited portion of said combustable material from being forced out of said enclosure means under the influence of centrifugal force resulting from the rotation of said device sufficiently to prevent cessation of ignition of said time delay fuse, said radially inwardly extending portion defining a relatively restricted discharge orifice through which the products of combustion of said combustable material are expelled, said orifice being located substantially coaxially of the axis of rotation of said housing.

2. A rocket device as set forth in claim 1 which includes a generally cylindrical shaped enclosure member for supporting said combustable material within said housing, said member including means defining a discharge opening and an inwardly extending

wall portion arranged circumjacent said opening and adapted to prevent said combustable material from being forced out of enclosure member upon rotation of said device.

5 3. A rocket device as set forth in claim 1 wherein said means for imparting rotary motion to said device comprising a plurality of canted discharge openings provided in the lower end of said housing, wherein said enclosure means comprises a generally cylindrical shaped enclosure communicable at one end with said explosion charge, the opposite end of said enclosure including a generally restricted discharge opening located substantially coaxially of the axis of rotation of said housing defined by an inwardly extending wall adapted to prevent the combustable material within said enclosure from being forced outwardly therefrom upon rotation of said device.

10 4. A rocket device as set forth in claim 2 wherein said inwardly extending wall portion encloses approximately one half of the lower end of said cavity.
